UNITED STATES PATENT OFFICE

2,498,980

SELF-FEEDING APPLICATOR

Robert B. Bowling and Laurence R. Bennett,
Hamilton, Ohio, assignors, by direct and mesne
assignments, of one-half to said Bowling and
one-half to Frank Cources, Hamilton, Ohio

Application October 8, 1947, Serial No. 778,664

2 Claims. (Cl. 101—327)

1

This invention relates to a self-feeding or fountain applicator for paint and other coating materials and has for one of its objects the provision of means whereby paints and other coating materials may be applied to various surfaces in a more efficient and satisfactory manner than heretofore.

Another object of the invention is to provide a self-feeding applicator of the class described which is simple of construction and which may be fabricated economically and sold to consumers at a low cost.

A further object is to provide means whereby a self-feeding applicator may be easily and quickly disassembled for cleaning after use.

Another object is to provide means in a structure of the character stated, whereby refilling of the reservoir with coating material is facilitated, and accomplished with a minimum of inconvenience to the user.

Another object is to provide a self-feeding roller type of applicator having means for applying decorative markings to a surface, with ease and at a rapid rate of progress.

These and other objects and advantages are attained by the means described herein and illustrated upon the accompanying drawing, in which:

Fig. 1 is a plan view, partly in cross-section, of the applicator of the present invention.

Fig. 2 is a fragmental cross-sectional view of the applicator taken on line 2—2 of Fig. 1.

Fig. 3 is a perspective view of an agitator attachment for the applicator.

Paint applicators of the general character herein disclosed have not heretofore enjoyed a substantial amount of popularity, due to certain structural faults which detracted from their utility and convenience of manipulation. The most common form of roller applicator available at the present time is one illustrated by U. S. Patent No. 2,411,842, issued December 3, 1946, to R. C. Adams. To use the Adams device, it is customary for the operator to dip the roller into a can of paint or other coating substance, and then squeeze out the excess by hand before the roller can be applied to the wall or other surface to be coated. With repeated dipping and hand squeezing in the course of a painting job, the obvious result is a waste of paint and a tendency to keep the hands soiled throughout the entire painting process. The inconvenience and disagreeable confusion resulting from this has discouraged universal adoption of the device for painting purposes.

The superiority of the device of the present

invention over prior devices of the same class will become evident as the description thereof proceeds. Attention is directed to the fact that the simplicity of construction of the applicator does not sacrifice any of its efficacy.

Referring to Fig. 1, the applicator comprises a hollow roller 4 rotatably mounted upon a handle member 5, the roller comprising a perforated cylinder 6 which is embraced by a plain or decorated cover or tube of pile fabric 7, or other resilient material of suitable porosity. The perforations of cylinder 6 are indicated at 8. One end of the cylinder 6 is closed by means of a fixed plug 9, which may be pressed in, sweated on, or otherwise preferably fixed against displacement. The fixed plug 9 is provided with a circumferential flange 10, substantially larger in diameter than the diameter of the cylinder 6, which cooperates with a similar flange 11 on the removable plug 12 at the opposite or charging port end of the cylinder 6 to confine the tube or cover 7 against displacement from the said cylinder. It will be noted that the tube 7 is substantially the same length as the cylinder 6.

25 The fixed plug 9 is provided with an axially aligned blind hole 13 into which is journaled the roller shaft 14, said shaft being, by means of the blind hole 13, in leak-proof relation to the fixed plug 9. Suitable means for precluding endwise movement of the roller shaft 14 is provided, the exemplified form being a retaining pin 15 pressed into an aperture 16, Fig. 2, provided transversely of the fixed plug inner hub 18 and adapted to engage a circumferential groove 19 provided on the roller shaft 14.

30 The handle arm 20 may be provided with a collar 21, which may be welded to the end thereof, as shown, said collar being in fixed engagement with the roller shaft reduced diameter 22 by means of peening, as indicated at 23, Fig. 1. Other means of fixing the handle collar 21 to the roller shaft 14 may be employed, such as a pin, setscrew, or weld.

35 The closure member or plug 12 at the charging port 24 may threadedly engage the interiorly threaded cylinder 6, as indicated at 25, to the limit imposed by the circumferential flange 11. The plug 12 may be provided with a transverse slot 25a upon its outer face for the application of a screw driver, coin or other suitable tool or article to aid in unscrewing the plug for filling or cleaning the cylinder 6. Detachment of the removable plug 12 permits removal of the fabric tube 7 for cleaning or replacement purposes, said tube, as hereinbefore recited, being confined between

the plug flanges 10 and 11 during use of the applicator. Means other than screw threads, of course, may be employed to afford the desired removability of the plug 12.

The handle member 5, as shown in Fig. 1, is preferably offset or formed with the arm portion 20 bent at right angles substantially beyond the radius of the pile fabric tube 7 to form the supporting arm 26 which terminates substantially centrally between the ends of said tube 7, and bent again at right angles to form the handle shank 28. The latter may be of any desired length, and may have fixed to its free end a suitable hand grip 29. The axis of the handle member 5 is preferably substantially co-planar at all points with the axis of the applicator roller.

As previously suggested herein, the tube or cover 7 may have a plain working surface when flat painting or coating is to be performed; however, should the operator desire to apply a decorative design to the surface undergoing treatment, he may substitute for the plain cover or tube one which carries a design such as 30. The design preferably is in relief as shown upon the working face of the cover, and may be porous like the cover, or possibly impervious depending upon the nature of the decoration desired. When only the design 30 is to carry the paint to the surface to be decorated, it will be desirable to make the design porous and to increase the extent to which it extends from the surrounding surface of the cover material. These considerations are subject to various modifications, as may be evident.

In some instances, it may be desirable to furnish means within the roller or cylinder to keep the paint or coating material thoroughly mixed during use of the applicator. This may conveniently be accomplished by furnishing a suitable agitator, one form of which is illustrated by Fig. 3. As there shown, the agitator comprises a pair of plates 31, preferably of thin sheet metal, each bent to provide vanes or partition members 32 and 33 having an intermediate flattened portion 34, the portions 34 being in flatwise contact and secured together in any suitable manner as by means of screws or rivets 35, or by welding, crimping, or other common practice. The vanes of each plate may be angularly related to one another at approximately 90 degrees divergency. The agitator as shown in Fig. 3 should be so dimensioned as to fit wholly within the cylinder or roller 6, with frictional contact between the cylinder wall and the vanes sufficient to enforce rotation of the agitator with the cylinder. To ensure the desired frictional contact, the longitudinal margins of the vanes may be turned as indicated at 36 to provide flexible flanges 37 adapted to resiliently bear against the inner face of the cylinder wall. At intervals, the vanes may be perforated or notched along the flanges 37, as at 38, to permit a flow of paint or coating material from one agitator compartment to another as the cylinder rotates during use of the applicator.

It will readily be evident that the agitator may comprise any number of vanes or partitions, and means other than the resilient flanges 37 might be employed to substantially fix the agitator within the cylinder. The agitator may be supplied as an attachment, if desired, or it may be part of the applicator as originally assembled.

From the foregoing specifications and accom-

panying drawings it is obvious that the device of the present invention offers substantial improvements over former coating applicators, in both construction and use. The perforated cylinder may be fabricated from any suitable metal, plastic, or composition material, and the tube or cover 7 is likewise subject to change of materials.

It is to be understood, of course, that various structural changes and modifications may be made within the scope of the appended claims, without departing from the spirit of the invention.

What is claimed is:

1. In an applicator for paint, the combination of a hollow cylindrical roller having a stiff per-
15 ous wall and having a closure plug in one end provided with a bearing, a removable filler plug normally closing the other end of said roller, a handle, means for mounting said handle in said bearing whereby said roller may be rotated about its longitudinal axis, and an agitator and spreader inside said cylinder, said agitator and spreader comprising a plurality of flat vanes extending radially from the longitudinal axis of the roller,
20 said vanes being attached together at the center of said roller and having their outer edges bearing on inner walls of the roller, the outer edges of the vanes being slotted to permit controlled amounts of the coating material to flow through
25 30 the slots to pass the vanes as the roller rolls.

2. In an applicator for paint, the combination of a hollow cylindrical roller having a stiff per-
35 ous wall, said wall including an inner perforate metal cylinder and an outer covering of per-
vious fabric material, said roller having a clo-
sure plug in one end provided with a bearing, a removable filler plug normally closing the other end of said roller, a handle, means for mounting said handle in said bearing whereby said roller
40 may be rotated about its longitudinal axis, and an agitator and spreader inside said cylinder, said agitator and spreader comprising a plurality of flat vanes extending radially from the longitudinal axis of the roller, said vanes being attached together at the center of said roller and having their outer edges bearing on inner walls of the roller, the outer edges of the vanes being slotted to permit controlled amounts of the coating material to flow through the slots to pass the vanes as the roller rolls, the paint passing through the perforations and penetrating the fabric cover, the metal cylinder holding the outer cover firmly in cylindrical shape.
